(57) **CLAIM**

The ornamental design for a computer generated image for a display panel or screen, as shown and described.

DESCRIPTION

FIG. 1 is a front view of a computer generated image for a display panel or screen showing my new design;

FIG. 2 is a front view a second embodiment thereof;

FIG. 3 is a front view a third embodiment thereof;

FIG. 4 is a front view a fourth embodiment thereof;

FIG. 5 is a front view a fifth embodiment thereof;

FIG. 6 is a front view a sixth embodiment thereof;

FIG. 7 is a front view a seventh embodiment thereof;

FIG. 8 is a front view an eighth embodiment thereof;

FIG. 9 is a front view a ninth embodiment thereof;

FIG. 10 is a front view a tenth embodiment thereof;

FIG. 11 is a front view an eleventh embodiment thereof;

FIG. 12 is a front view a twelfth embodiment thereof;

FIG. 13 is a front view a thirteenth embodiment thereof; and,

FIG. 14 is a front view a fourteenth embodiment thereof.

The broken line drawings of a display panel or screen in all views and the interior elements in FIGS. 2-7, 9-14 are for illustrative purposes only and form no part of the claimed design.
